UNITED STATES PATENT OFFICE

WILLIAM J. ADAMS, OF SANTA CRUZ, CALIFORNIA, ASSIGNOR TO BALL WAGON GRADER COMPANY, OF STOCKTON, CALIFORNIA, A CORPORATION

SCRAPER-BOWL CONSTRUCTION

Application filed November 6, 1928. Serial No. 317,628.

This invention relates to scraper bowls and especially to one of that character having a discharge gate at its rear end and which is dumped by raising up the front end of the bowl. The structure of the present invention also particularly represents improvements over the type of bowl and discharge gate shown in the patent to C. E. and S. H. Ball, No. 1,593,007, dated July 20th, 1926.

In the previous type of bowl the gate was so mounted that when opened there was a tendency for the dirt, especially if wet or of a heavy nature, to catch thereon and to wedge in the bowl, so that it would fail to be properly discharged. Also the gate when opened became lowered to a considerable distance below the bottom of the bowl which interfered with the leaving of the dirt in a compact heap as the scraper moved forward. A major object of the present invention therefore is to so shape and mount the discharge gate as to avoid these objectionable features.

Other features of improvement of the present bowl construction consist in providing a removable cutting blade for the bowl so that said blade may be easily changed or resharpened, and to apply the raising members to the bowl so that a stronger connection is made and the lifting is accomplished with a lesser expenditure of power.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claim.

In the drawings similar characters of reference indicate corresponding parts in the several views:

Fig. 1 is a sectional elevation of my improved bowl as mounted in connection with its supporting and operating structure showing the bowl in its digging position.

Fig. 2 is a side elevation of the bowl in a raised or discharging position and with the gate open, also shown associated with its supporting structure.

Referring now more particularly to the

characters of reference on the drawings, the bowl comprises a substantially flat bottom plate 1 and side plates 2. The forward edges of these side plates extend upwardly at substantially a right angle to the bottom plate for a relatively short distance as at A, and then slope upwardly and rearwardly for a greater distance as at B. The rear edges of the side plates have a continuous concave curvature (relative to the front edge) as shown at C, and extend from the top of said front edge to the rear edge of the bottom plate.

The rear end of the bowl is normally enclosed by a gate 3 which extends from top to bottom of the curved back edge of the side plates and has the same curvature. Said gate also aligns with said curved edge when closed. Large side ears or plates 4 secured to the end gate extend from the top to bottom thereof and have a running fit between the side plates of the bowl. Bolts 5 connect the ears and the side plates and form the pivot or hinge means for the gate, these bolts being positioned in a longitudinal plane some distance rearwardly of the junction of the rear and front edges of the sides, and in a horizontal plane some distance below said junction.

The front end of the bowl is reinforced by a relatively heavy and wide strap 6 which is riveted to and extends across the bottom plate and up the vertical portions A of the side plates, said strap being on the outside of the bowl and projecting ahead of said bottom and side plates somewhat. To the bottom portion of the strap a cutting blade 7 is removably secured, said blade extending from and lying flush with the forward edge of the bottom of the bowl to a point some distance ahead of the strap, as shown in Fig. 1. The front edge of the strap is also preferably beveled off as at 8 to form an auxiliary cutting edge.

As in the previous type of bowl, this bowl has three connections with the frame structure 9 in which it is mounted. These connections comprise substantially vertical links 10 connected to the sides of the bowl at the rear end and to the frame above; tension bars 11 connected to the side plates near the front and

intermediate the top and bottom thereof, and to the frame ahead; and control cables 12 or the like connected to the straps 6 adjacent the top thereof and extending thence vertically to and over sheaves 13 mounted on the frame. 5 The cables therefore are connected to the bowl at such points relative to the links 10 as to obtain a very advantageous leverage when lifting the bowl; and such connections being made directly with the heavy straps 6 are 10 very substantial without any undue strain being placed on the relatively thin side frames of the bowl.

Pulling up on these cables as before raises the front end of the bowl and the rear end 15 also, but a lesser distance, the end-gate being then forced open by the pressure of the load in the bowl as soon as the holding latch means 14 is released. Owing to the positioning of the pivot or hinge connections of the gate 20 with the side plates, a wide opening is provided between the bottom of the gate and the rear end of the bowl without an excessive opening movement of the gate being necessary, so that the dirt in the bowl will not be 25 choked or restricted in any way in its discharge. Also on account of such positioning of the pivots the bottom of the gate when 30 opened is not positioned as low as the rear end of the bowl so that it will not engage and drag against the dirt after the latter is discharged and the scraper is moved forward.

The end-gate having a continuous and smooth curvature, not only gives the bowl a 35 large holding capacity but allows the dirt to slide freely from said gate, without any tendency for some of the dirt to be restrained and pocketed. The side plates or ears on the gate apart from reinforcing the same tend 40 to scrape the sides of the bowl clean as the gate closes, thereby dislodging any dirt which might tend to cling thereto.

From the foregoing description it will be readily seen that I have produced such a device as substantially fulfills the objects of the 45 invention as set forth herein.

While this specification sets forth in detail the present and preferred construction of the device, still in practice such deviations 50 from such detail may be resorted to as do not form a departure from the spirit of the invention, as defined by the appended claim.

Having thus described my invention what I claim as new and useful and desire to secure by Letters Patent is:

A scraper bowl having bottom and side plates, an end-gate extending between the side plates and alining with the rear edges thereof when the gate is closed, ears on the 60 edges of the gate having a running fit between the side plates of the bowl, pivots between the ears and bowl nearer the top than the bottom thereof, the forward edges of the ears having a slight inclination forwardly from 65 the upper rear corners of the side plates to

points adjacent the pivots, and a slight reverse inclination from those points rearwardly to the lower rear corners of the side plates.

In testimony whereof I affix my signature.

WILLIAM J. ADAMS.
